US00D821468S

(12) **United States Design Patent** (10) **Patent No.:** **US D821,468 S**
Alfaro et al. (45) **Date of Patent:** **** Jun. 26, 2018**

- (54) **CERAMIC BONDING TOOL WITH TEXTURED TIP**
- (71) Applicant: **COORSTEK, INC.**, Golden, CO (US)
- (72) Inventors: **Cesar Alfaro**, Lewisville, TX (US); **Russell Bell**, Ventura, CA (US); **Anne Cenedella**, Evergreen, CO (US); **Steve Govorchin**, Superior, CO (US); **Mark S. Greenwell**, Ventura, CA (US); **Brian Seegmiller**, Arvada, CO (US); **Matthew Simpson**, Evergreen, CO (US)
- (73) Assignee: **CoorsTek, Inc.**, Golden, CO (US)
- (**) Term: **15 Years**
- (21) Appl. No.: **29/612,575**
- (22) Filed: **Aug. 2, 2017**

(57) **CLAIM**

The ornamental design for a ceramic bonding tool with textured tip, as shown and described.

DESCRIPTION

FIG. 1 depicts a perspective view of a ceramic bonding tool with textured tip.

FIG. 2 depicts a side elevation view of the ceramic bonding tool with textured tip of FIG. 1.

FIG. 3 depicts a top plan view of the ceramic bonding tool with textured tip of FIG. 1.

FIG. 4 depicts a bottom plan view of the ceramic bonding tool with textured tip of FIG. 1.

FIG. 5 depicts detailed side elevation view of the ceramic bonding tool with textured tip of FIG. 1.

FIG. 6 depicts a detailed bottom plan view of the ceramic bonding tool with textured tip shown in FIG. 4; and, FIG. 7 depicts a detailed side cross-sectional view of the ceramic bonding tool with textured tip, the cross-section taken along cross-section indicator line 7-7 of FIG. 6.

The broken lines in the drawings illustrate environmental structure on the article and form no part of the claimed design.
